UNITED STATES PATENT OFFICE.

GEORGE E. LARSEN AND ALFRED K. JOHNSON, OF CHICAGO, ILLINOIS.

RADIATOR-COVER.

No. 923,668.

Specification of Letters Patent.

Patented June 1, 1909.

Application filed March 7, 1908. Serial No. 419,629.

To all whom it may concern:

Be it known that we, GEORGE E. LARSEN and ALFRED K. JOHNSON, a citizen of the United States and a subject of the King of Norway, respectively, residing at Chicago, in the county of Cook and State of Illinois, have invented a certain new and useful Improvement in Radiator-Covers, of which the following is a full, clear, concise, and exact 10 description, reference being had to the accompanying drawings, forming a part of this specification.

Our invention relates to devices to be used in connection with steam or other radiators, 15 and its object is to provide a simple, practical and inexpensive device which will serve not only as a cover or fender for the radiator, but will also serve to diffuse moisture in the room where the radiator is located 20 and thereby make the room more sanitary.

In the accompanying drawings Figure 1 is a view in vertical section of a radiator cover embodying our invention and a part 25 of a radiator supporting the same. Fig. 2 is a front view of a radiator with the cover on it.

The device shown in the drawings for carrying out our invention comprises a casing desirably made out of sheet metal and having 30 a front 1 substantially vertical in its middle portion and having its upper portion 2 bent backwardly so as to extend to the back of the radiator. On the sides of the front 1 are two sides 3-3, which are also desirably 35 flat sheet metal pieces widest at their upper ends and tapering substantially to a point at their lower ends, where they are connected with the bottom of the front 1.

A reservoir 4 conveniently in the shape 40 of a trough is arranged within the chamber formed by the front 1 and the sides 3-3, and is secured at 5 to the top over-hanging portion 2 of the front 1. This reservoir desirably extends from side to side of the device, and is substantially closed, except that it has a longitudinal slot 6 at its rear upper edge, through which vapors from the reservoir can pass. It is conveniently provided 45 with an upwardly extending tongue 7, by 50 which it can be filled.

The device is also provided with supporting members 8-8, conveniently in the form of wire rods, secured to the back 1 and bent upwardly and backwardly so that they can 55 engage lugs on the radiator when the device is placed upon the same. Thus it will be

seen that the device can be placed upon a radiator and when so placed it will serve as a cover or shield for the same, and at the same time it will be heated by the radiator, and when so heated the water will slowly evaporate, so that it will pass out into the room and furnish enough moisture to prevent bad effects from dryness to the people and furniture in the room. 65

What we claim as our invention is:

1. A radiator cover comprising a hood adapted to fit over the top of the radiator and extend part way down the same, means for hanging the hood on the radiator, and a reservoir carried by the hood and arranged to deflect the vapors out into the room. 70

2. A radiator cover comprising a hood adapted to fit over and partially cover the upper portion of the radiator, means for hanging the hood or cover upon the radiator, and a reservoir supported by the hood and having an opening which faces backwardly at the rear of the hood so as to direct the products of evaporation rearwardly from 80 the hood and into the room.

3. A radiator cover comprising a hood having a front and side walls extending part way down the radiator, curved rods 8-8 secured to the front of the hood and extending rearwardly therefrom and arranged to engage the lugs or projections upon the sections of the radiator, and adapted to be interposed between adjacent sections to engage 85 said lugs so as to hang the cover upon the 90 radiator.

4. A radiator cover comprising a hood having a front and side walls extending part way down the radiator, curved rods 8-8 secured to the front of the hood and extending rearwardly therefrom and arranged to engage the lugs or projections upon the sections of the radiator, and adapted to be interposed between adjacent sections to engage 95 said lugs so as to hang the cover upon the 100 radiator, and a reservoir supported by the hood above the radiator and having an opening at its rear opening out into the room, so as to direct the vapors into the same.

5. A device of the class specified, comprising a member adapted to be mounted upon the radiator, means for hanging the same upon the radiator, and a reservoir supported by said member above the radiator and arranged to direct the vapors into the room. 105

6. A device of the class specified, comprising a hood having a front, and also having 110

rods 8—8 secured to said front and extended rearwardly from the same, said rods being adapted to engage lugs on the radiator and to coöperate with the front of the hood in 5 making a tight connection between the radiator and the hood.

7. A device of the class specified, comprising a hood having a front, and also having rods 8—8 secured to said front and extended 10 rearwardly from the same, said rods being adapted to engage lugs on the radiator and to coöperate with the front of the hood in

making a tight connection between the radiator and the hood, and a reservoir supported by the hood above the radiator and 15 having an opening adapted to cause the vapors to issue into the room.

In witness whereof, we hereunto subscribe our names this 4th day of March A. D., 1908.

GEORGE E. LARSEN.
ALFRED K. JOHNSON.
